UNITED STATES PATENT OFFICE.

HARRY L. FELLOWES, OF CHICAGO, ILLINOIS, ASSIGNOR TO BANKERS BOX COMPANY, OF CHICAGO, ILLINOIS, A CORPORATION OF ILLINOIS.

FOLDABLE BOX AND BLANK THEREFOR.

1,369,642.

Specification of Letters Patent. Patented Feb. 22, 1921.

Application filed June 10, 1918. Serial No. 239,094.

To all whom it may concern:

Be it known that I, HARRY L. FELLOWES, a citizen of the United States of America, and a resident of Chicago, county of Cook, and State of Illinois, have invented certain new and useful Improvements in Foldable Boxes and Blanks Therefor, of which the following is a specification.

My invention relates to foldable boxes and has for its object improvements in such devices.

In the accompanying drawings—

Figure 1 is the blank from which the box is formed;

Fig. 2 is the same blank on a larger scale, but partly folded, and with attachments secured thereto;

Fig. 3 is the box in finished form; and

Fig. 4 is an enlarged cross-section of the completed box near one end.

Referring to Fig. 1, the part S of the blank between the dotted lines 10 and 11 form the sides S' and ends E of the finished box. The parts T of the blank form the top of the finished box, and the parts B form the bottom thereof. The dotted lines 10 and 11 represent lines along which the blank is folded.

In the blank are cut slots 12, 13, 14, 15, 16 and 17. These slots extend from the outer edges to the folding lines 10 and 11. Part of the material between slots 15 and 16, and part of that beyond 17, is preferably removed as shown. Corrugated pasteboard is good material from which to form the blank.

Assume the portion of the blank to the left of the cuts 12—17 to be folded over along the line of those cuts and upon the remainder of the blank. Also, assume the portion to the right of the cuts 14—15 to be similarly folded along the line of those cuts. The extreme ends of the blank will then be brought together at line 18 of Fig. 2. The two ends are then secured together by a gummed piece of cloth 19.

Another piece of gummed cloth 20 is secured along the outer edge of that part D of the blank which is outside of the line 11 and cut 12. This piece 20 is at this stage secured only along its central portion, the ends being free. The free part is that shown extending to the right of the line 18, and to the left beyond the edge of the blank as shown in Fig. 2.

Also, another piece of gummed cloth 21, of

the same size and shape as 20, is secured to the corresponding part H of the blank which lies between cuts 13 and 14.

Eyelets 22 are secured in the outer corners of the parts T. Other eyelets 23 are secured in the shortened parts F and G. And still other eyelets 24 are secured in the part which forms the ends E of the completed box. In these eyelets at each end is threaded a cord or tape C. Secured in each end E is a button M.

The box lying flat as shown in Fig. 2 is in the condition in which it is shipped or delivered to the trade. Before leaving the factory, however, the board is broken, that is bent, along the lines 10 and 11, and also along the lines 12—17, 13—16 and 14—15. The box is finished at the place where it is to be used.

To finish or complete the box, the parts are shifted manually from flat to rectangular form. This is possible by reason of the patch or gummed piece 19 connecting the two ends of the blank to form one corner, the other corners being at the bends which are along the lines of the cuts before mentioned.

As soon as the rectangular shape is thus obtained, the bottom flaps B are folded inward to form a bottom to the box, and the end flaps D are folded toward each other over the ends of the bottom flaps B. When this position is reached, the free ends of the gummed patches 20 and 21 are moistened and pasted against the sides S' as shown in Figs. 3 and 4.

At this stage of the proceedings there is a complete box having an open top. To close the box, the short flaps F and G are bent inward, and the flaps T are similarly bent. The cords C are then pulled tight and wound upon the buttons M. The box is opened by releasing the cords from the buttons and lifting the tops T. As shown in Figs. 3 and 4, it will be seen that the cords C, when pulled out and wound upon the buttons M, serve to draw the flaps T down so as to close the top of the box and hold said flaps in that position. As shown in Fig. 2, it will be seen that, when the cords are released from the buttons and the flaps lifted, the cords passing through the ends E serve to limit the outward movement of the flaps T, F, and G. As the boxes are made from corrugated pasteboard, such limitation by the cords serves to prevent injury at the hinge.

connections along the line 10 between the sides S and the flaps due to frequent opening and closing of the box, and the bending of the flaps outward when opened.

5 It is to be observed that in making this box there is practically no waste of material. The small amount cut from the flaps F and G being for convenience and not by reason of necessity. The bottom flaps B meet each 10 other at the center line of the box, and are held in place by the flaps D and H which in turn are secured by the gummed pieces or patches 20 and 21. The top flaps T also meet on the center line of the box and are held 15 down by the cords C.

To have the flaps B and T meet at the center line of the box, the width of each of these flaps must be equal to one-half of the length of the flap H between the cuts 13 and 20 14. Also, there is the same relationship to the flap D because D and H are of the same size. The relationship here stated is not to the flaps H and D as such, but to the distance between the bends in the central part 25 S which come on the lines of the cuts 13—16 and 14—15. By making the cuts 12 to 17 wider, the parts H and D would be shorter without changing the construction. However, these cuts are preferably of a width 30 which equals the thickness of the material used, and are herein referred to as if they were mere lines without width. These cuts or lines come at the corners of the completed box.

What I claim is:

35

1. A box formed of a single piece of bendable material scored on parallel lines to form side, end, top and bottom walls, one end of said blank and the intermediate portion being transversely cut laterally of the side and end 40 walls and bendable on said parallel lines to provide end retaining flaps for the bottom walls, and supporting flaps for the top walls and a tie cord for holding the box in set up formation passing through the ends of the 45 top walls, supporting flaps and end walls with the outwardly extending end of the cord secured to the end wall to hold the end walls and top wall relatively immovable.

2. A box formed of a single piece of bendable material scored on parallel lines to form side, end, top and bottom walls, one end of said blank and the intermediate portion being transversely cut laterally of the side and end walls and bendable on said parallel 55 lines to provide end retaining flaps for the bottom walls and supporting flaps for the top walls, the area of the supporting flap being reduced to provide a substantially unobstructed opening in the top of the box and 60 a tie cord for holding the box in set up formation passing through the ends of the top walls, supporting flaps and end walls with the outwardly extending end of the cord secured to the end wall to hold the end walls and top wall relatively immovable.

HARRY L. FELLOWES.
